UNITED STATES PATENT OFFICE.

BENJAMIN LIEBOWITZ, OF NEW YORK, N. Y.

ARC OSCILLATION-GENERATOR.

1,271,183.

Specification of Letters Patent.

Patented July 2, 1918.

Application filed January 28, 1915. Serial No. 4,965.

To all whom it may concern:

Be it known that I, BENJAMIN LIEBOWITZ, a citizen of the United States, and a resident of New York, in the county of New York and 5 the State of New York, have invented certain new and useful Improvements in Arc Oscillation-Generators, of which the following is a specification.

My invention relates to the art of generating high frequency electrical oscillations, such as are used, for example, in radio-telegraphy and telephony. The object of my invention is to provide a simple and inexpensive generator for producing 15 electrical oscillations.

One form of my invention consists of a vapor electric device having two cathodes and an anode. Each cathode is connected to the negative terminal of a high-voltage 20 source of direct current through a large inductance and a resistance; and the anode, likewise through an inductance, to the positive terminal. An oscillatory circuit is shunted between the cathodes.

25 The above will be more readily understood by reference to the drawings in which Figure 1 is a diagrammatic view of my invention used in connection with a mercury vapor tube, the tube being partly in section, 30 and Fig. 2 is a diagrammatic view of a modification which enables alternating current source to be used, a single tube being employed for rectifying and for generating the oscillations.

35 Referring to Fig. 1, a source of high voltage direct current such as a high voltage dynamo, is shown at 1, with plus and minus terminals as indicated. To prevent high frequency energy from getting back 40 into the supply circuits, I provide an inductance shown at 2, although any other suitable means may be employed for this purpose. 3 designates a mercury vapor tube having an anode 4, and two mercury cathodes, 5 and 6. Cathode 5 is connected to the negative terminal of 1 through a large inductance 7 and a resistance 9, and cathode 6 is likewise connected through the inductance 8 and resistance 10. Since these cathodes alternately carry the main current through the tube, they may be called "arc- 45 ing cathodes." Inductance 7 and resistance 9 may be conveniently combined into a single coil having proper inductance and resistance. Likewise 8 and 10. Inductances 2, 7 and 8 should preferably be wound so

as to have minimum distributed capacity. An oscillatory circuit, comprising, for example, a condenser 11 and inductance 12, is connected between the cathodes as shown. 60 The tube may be started in a variety of ways, well known in the art. The method shown here is as follows: A switch 13 in the oscillatory circuit is opened, and a double throw switch 14 is thrown to the left. 65 These positions are shown by the dotted lines in the figure. The cathode 6 is thus temporarily made a starting anode, and by tilting the tube in the usual manner, the discharge through cathode 5 is started and 70 will be maintained. Switch 14 is now thrown to the right, the position shown in the drawing by the full lines, and if the tube is again tilted, cathode 6 will be started. Two such parallel discharges are ordinarily 75 highly unstable, but if each cathode is supplied through a suitable inductance, as shown, the parallel discharges are rendered stable and will run indefinitely under suitable conditions. 80

The stability produced by the inductance in series with each cathode is destroyed if a condenser is shunted across the cathodes, and it is owing to this fact that the system can be made to oscillate. One mode of operation is as follows: 85

Suppose that the parallel discharges are operating steadily, the switch 13 being open. Let this switch now be closed, (position shown by the full lines); the stability of the 90 parallel discharges is destroyed, and one of them, say that through 5, will be extinguished. The current through inductance 7, which formerly went through 5, must now take the path from 4 through 6, 13, 95 12, 11 and 7; that is, the inductance 7 now begins to discharge itself into condenser 11. In a very short time the condenser attains a voltage, say V , sufficient to start a discharge in the tube between 5 and 6, hence 100 the oscillatory circuit begins to execute an oscillatory discharge around the path 11, 12, 13, 6, 5, 11. Discharging under ordinary circumstances the condenser would attain at the end of the first half-swing a voltage 105 $-(V-v)$ which is reversed in sign to the original voltage V and smaller in value than V . But as soon as the condenser circuit begins to discharge through the tube, cathode 5 is started again and cathode 6 extinguished. The current through inductance 110 8 must now pass through cathode 5, hence

while the oscillatory circuit is executing its first half-swing, inductance 8 is discharging into condenser 11. At the end, or shortly before or after the end, of the first 5 half-swing, therefore, the condenser voltage will not be $-(V-v)$ but $-V$, which voltage is sufficient to start the reverse discharge between 5 and 6. The condenser circuit now begins to execute its second half-swing, 10 starting cathode 6 and extinguishing cathode 5 again. The condenser voltage tends toward the maximum value $(V-v)$, but the inductance 7 must now discharge into the condenser, so that the voltage V is reached 15 again, and the process repeats itself.

When the system is operating in the manner described the oscillations produced are undamped and practically sinusoidal. The system may oscillate in other ways, however, 20 giving for example rapid series of slightly damped waves, or other types of waves. The manner in which the system oscillates is determined by the magnitude and character of the various constants which enter into 25 the circuits.

In the drawing the cathodes 5 and 6 are shown constricted where the discharge enters them. I prefer to make the cathodes in this form because better results have been 30 obtained with them than with mercury pools of the ordinary type.

It is found by experiment that in order to obtain steady oscillations the ratio of inductance to capacity in the oscillatory circuit must be very large. The oscillatory circuit can be connected or coupled to the antenna or other circuits in any desired manner; and, under proper conditions, the antenna itself may be the oscillatory circuit 40 or part thereof.

My invention may be adapted for use with alternating current supply. Single phase may be employed, but I prefer to use poly-phase. Referring to Fig. 2, which shows my 45 invention adapted for use on a two-phase system, 20A and 20B indicate the two-phase supply, 21 and 23 are the primaries of a pair of transformers, 22 and 24 are the secondaries of the same. The primaries are supplied through the series reactances 25 and 26. The tube 3 is provided with four anodes, 4^a, 4^b, 4^c, and 4^d. Special care is necessary to prevent arcing between these anodes. The terminals of 22 are connected 50 to anodes 4^a and 4^b, those of 24 to 4^c and 4^d. The mid-points of the secondaries 22 and 24 are connected together, and from these mid-points run the parallel paths 7, 5 and 8, 6. The significance of these and the remaining 55 members is the same as in Fig. 1. In order not to complicate the figure, starting means are not shown. The tube may be started as shown in and described in connection with Fig. 1, or in a variety of other ways. 60 It is understood, of course, that means are

provided for preventing high frequency energy from getting back into the supply circuits.

Such means may be incorporated in the 70 transformers themselves, for example.

It will be observed that the extra resistances 9 and 10 of Fig. 1 are not shown in Fig. 2, and that series reactances 25 and 26 are shown in Fig. 2, through which the primaries are supplied. The reason for this is 75 as follows: In Fig. 1 the extra resistances are necessary in order to limit the starting current, that is, the current drawn by the circuits after the parallel discharges are started and before the oscillations have been set 80 up. In Fig. 2, however, where alternating current is employed, the starting current is limited by the series reactances 25 and 26, hence only small series resistances are necessary; hence the form shown in Fig. 2 is more 85 efficient than that in Fig. 1. If the transformers of Fig. 2 are constructed to have sufficient leakage, then the series reactances are unnecessary. All that is necessary is a loose coupling between the primaries and 90 secondaries of the supply circuits.

The form of my invention shown in Fig. 2, is designed to work on an alternating current supply, and accordingly performs the function of rectification as well as generation. The rectifying action which takes 95 place is well understood in the art. The use herein described of an alternating current supply loosely coupled to rectifying circuits and an arc oscillation generator gives improved efficiency in any arc oscillation generator.

I have shown my invention used in connection with mercury arcs *in vacuo*, but my invention is not to be construed as limited to these arcs, as the double cathode method herein described may be employed in connection with any of the arcs which may be used for generating oscillations, whether vapor arcs *in vacuo* or otherwise, of the type in 105 which the source of instability lies at the cathodes and not in the positive column. It should be noted that my invention differs from the previous devices employing double discharges in that in my device the discharge 110 of the cathode is through a common positive column to a common anode, whereas in the previous devices the two discharges are independent throughout their entire lengths. This distinction is exceedingly important, 115 for it has been demonstrated experimentally that when two ordinary carbon arcs are merged so as to discharge to a common positive crater the instability arising upon shunting a condenser across the cathodes is 120 greatly reduced as compared with the instability when the two arcs are not merged. This is due to the fact that in the ordinary carbon arcs the source of instability is in 125 the positive column. In the mercury vapor 130

arc, on the other hand, as my experiments have demonstrated, the instability lies at the cathode. When it is desired to rectify and generate in a single arc, however, vapor arcs *in vacuo* must be employed, as shown in Fig. 2.

I have described certain specific forms of my invention, but the invention is not to be construed as limited to these specific forms.

10 What is claimed as new and original will appear from the appended claims.

I claim:

1. In an arc oscillation generator, the combination with a source of supply and a system of supply circuits, of a pair of arcing cathodes discharging through a common positive column, means for stabilizing parallel discharges from said cathodes, and an oscillatory circuit connected between said

20 cathodes.

2. In an oscillation generator, the combination with a source of supply and a system of supply circuits, of a vapor electric device, a pair of arcing vaporizable cathodes 25 in said vapor electric device discharging through a common positive column, means for stabilizing parallel discharges from said cathodes, and an oscillatory circuit connected between said cathodes.

3. In an arc oscillation generator, the combination with a source of supply and an anode, of a pair of arcing cathodes discharging through a common positive column to the anode, an inductance and resistance in 35 series with each of said cathodes, and an oscillatory circuit connected between said cathodes.

4. In an arc oscillation generator, the combination with a source of supply and an anode, of a pair of arcing cathodes discharging through a common positive column to the anode, an inductance in series with each of said cathodes, and an oscillatory circuit connected between said

5. In an arc oscillation generator, the combination with a source of supply and an anode in series with an inductance, of a pair of arcing cathodes discharging through a common positive column to the anode, an inductance and resistance in series with each of said cathodes, and an oscillatory circuit connected between said cathodes.

6. In an arc oscillation generator, the combination with a source of supply and an anode in series with an inductance, of a pair of arcing cathodes discharging through a common positive column to the anode, an inductance in series with each of said cathodes, and an oscillatory circuit connected between said cathodes.

7. In an oscillation generator, the combination with a source of supply and a vapor electric device, of a pair of arcing cathodes discharging through a common positive column in said vapor electric device, an inductance and resistance in series with each of said cathodes and an oscillatory circuit connected between said cathodes.

8. In an oscillation generator, the combination with a source of supply and a vapor electric device, of a pair of arcing cathodes discharging through a common positive column in said vapor electric device, an inductance in series with each of said cathodes, and an oscillatory circuit connected between said cathodes.

9. In a vapor arc oscillation generator, the combination with a source of supply and an anode, of a pair of arcing vaporizable cathodes discharging in common to said anode, an inductance and resistance in series with each of said cathodes, and an oscillatory circuit connected between said cathodes.

10. In a vapor arc oscillation generator, the combination with a source of supply and an anode, of a pair of arcing vaporizable cathodes discharging in common to said anode, an inductance in series with each of said cathodes, and an oscillatory circuit connected between said cathodes.

11. In a vapor arc oscillation generator, the combination with a source of supply and an anode in series with an inductance, of a pair of arcing vaporizable cathodes discharging in common to said anode, an inductance and resistance in series with each of said cathodes, and an oscillatory circuit connected between said cathodes.

12. In a vapor arc oscillation generator, the combination with a source of supply and an anode in series with an inductance, of a pair of arcing vaporizable cathodes discharging in common to said anode, an inductance in series with each of said cathodes, and an oscillatory circuit connected between said cathodes.

13. In an oscillation generator, the combination of an exhausted vessel, a pair of vaporizable cathodes and an anode in said exhausted vessel, said cathodes discharging through a common positive column to said anode, an inductance in series with said anode, a high voltage source of direct current, an inductance and resistance in series with each of said cathodes, through which inductance and resistance each of said cathodes is connected to the negative terminal of said source of direct current, said anode being connected to the positive terminal of said source of direct current, and an oscillatory circuit connected between said cathodes.

14. In an oscillation generator, the combination with a source of supply and a vapor electric device, of a pair of constricted arcing cathodes in said vapor electric device, an inductance and resistance in series with each of said cathodes, and an oscillatory circuit connected between said cathodes.

15. In an oscillation generator, the combination of a source of supply and a vapor

electric device, of a pair of constricted arc-
ing cathodes in said vapor electric device,
an inductance in series with each of said
cathodes, and an oscillatory circuit con-
nected between said cathodes.

16. In an oscillation generator, the combi-
nation with a source of supply and a vapor
electric device, of a pair of arc-
ing cathodes in said vapor electric device, an inductance
10 and resistance in series with each of said
cathodes, and an oscillatory circuit having
a large ratio of inductance to capacity con-
nected between said cathodes.

17. In an oscillation generator, the combi-
nation with a source of supply and a vapor

electric device, of a pair of arc-
ing cathodes in said vapor electric device, an inductance
in series with each of said cathodes, and an
oscillatory circuit having large ratio of in-
ductance to capacity connected between said 20
cathodes.

Dated, New York, Jan. 18, 1915.

In testimony whereof, I have hereunto
affixed my signature in the presence of two
subscribing witnesses.

BENJAMIN LIEBOWITZ.
